FIG. 1.

FIG. 2.

FIG. 3.

Heinrich Kuhle
Inventor:
by Mr. M. L. Murphy, Atty.

UNITED STATES PATENT OFFICE

HEINRICH MÜLLER, OF NUERMBERG, GERMANY

TOY

Application filed March 26, 1928, Serial No. 264,847, and in Germany January 9, 1928.

This invention relates to toys and more especially to toys representing a figure of an animal or the like which is operated by a mechanism in a manner to imitate natural motion. According to my invention the toy may imitate, for instance, the alternate downward and upward motion of a bird when picking up food from the ground. In addition to this according to my invention the toy 10 may be constructed that it will make a walking, dancing or similar motion.

Essentially my invention consists in a novel toy representing a figure of an animal, preferably a bird, which is mechanically driven by means of a clock-work. The principal novel feature of my invention consists in imparting to the toy a proper reciprocating or vibratory motion which imitates most closely the natural motion of an animal or bird. More particularly, this novel feature consists therein that an eccentrically mounted fly-wheel driven by a clock-work is provided within the body of the toy, said eccentrically 25 mounted fly-wheel imparting during rotation a reciprocating or vibratory motion to the toy. When using the term "fly-wheel" for the member which produces said reciprocating or vibratory motion of the toy I desire to be understood that this member is not necessarily of the conformation of a wheel, since any form of swinging body or the like may be employed which is rotated around a point essentially at a distance from its center of 30 gravity.

According to a further feature of my invention the aforementioned eccentrically mounted fly-wheel, swinging body or the like is arranged within the breast portion of the 40 toy in order to most naturally imitate the picking motion of a bird, while the toy is freely standing upon its feet. In addition to this, according to my invention said fly-wheel or the like is positioned within the 45 breast portion of the bird at a point outside of the plane of gravity or symmetry of the figure, so that the latter in addition to the aforementioned picking motion, will also make a hopping or dancing motion, thus imitating as closely as possible the natural motion.

tion of a bird, when picking up food from the ground.

In the following specification and accompanying drawing I have described and shown an exemplification of a toy constructed according to my present invention.

In the drawing, Fig. 1 shows the toy in the form of a bird in a lateral view partly broken away in order to expose the driving mechanism contained in the interior and serving to impart a motion to said toy in the direction of the dotted double arrow, said motion imitating the natural picking motion of a bird. The end positions of said motion of the body of the bird are indicated by the full-drawn normal position and the dotted picking position of the same. Fig. 2 is a top-view taken on Fig. 1, and is likewise shown partly broken away to show the driving mechanism of the toy, while Fig. 3 is a bottom-view taken on Figs. 1 and 2. The driving mechanism consists of an ordinary clock-work which is driven by spring power such as frequently used in toys of the present kind. The spring 8 after being wound-up by means of the stem 7 will rotate a train of gear-wheels diagrammatically indicated in Fig. 2. The several gear wheels are designated with the numerals 10, 17, 11, 13 and 14. The last driving axle 5 of the clock-work carries a fly-wheel 6 which is eccentrically mounted on said axle so that it will produce the above-mentioned downward and upward motion of the body of the bird. The clock-work is mounted within the body of the bird in such a manner that the fly-wheel 6 will be positioned between the beak and the legs of the bird. The fly-wheel 6 during being rotated by the clock-work will disturb in accordance with its speed of rotation the equilibrium of the entire body of the toy, so as to impart to the body of the bird in rapid succession an alternate, reciprocating or tilting motion. The relatively light body of the toy, which is preferably made of sheet metal and which may be provided with a proper covering of velvet or the like will easily assume a rapid alternate tilting motion during rotation of the eccentrically mounted fly-wheel 6. This tilting motion of the body of the bird will

most naturally imitate the motion of a bird during picking up food from the ground. An excessive tilting motion of the body of the bird towards the rear which may take place in case of an excessive action of the fly-wheel 6 may be effectively prevented by providing a relatively long rear toe, said toe in this case forming a brace against said tilting motion.

10 During the picking motion of the toy, which motion is due to the rotation of the eccentrically mounted fly-wheel 6, the beak and the toes will act as the extreme supporting points for the body of the bird so that 15 said motion will be limited by the beak and the toes.

In addition to this picking motion according to my invention also a slight walking motion may be imparted to the body of 20 the bird by means of the eccentrically mounted fly-wheel 6. In order to further render this latter motion more similar to the natural motion of a bird, the fly-wheel in addition to its eccentricity with respect to its axle is 25 furthermore displaced with respect to the plane of gravity of the toy or to the longitudinal plane of symmetry A-B of the body of the bird towards one or the other side thereof, as may clearly be seen from Fig. 2.

30 This one-sided arrangement of the eccentric fly-wheel 6 which is provided within the body of the toy, will have the effect that in addition to the above-described picking or tilting motion a walking, hopping or 35 dancing motion of the latter will take place, for instance, in a circular direction, as indicated by the dotted arrow shown in Fig. 2. By this the additional motion of the toy will be enabled to most naturally imitate the 40 actual motion made by a bird during seeking food and picking-up the same from the ground. The clock-work together with the fly-wheel which serves for mechanically actuating the toy and for effecting the afore- 45 described picking, dancing or similar motion is mounted in the ordinary manner within the body of the toy. The clock-work which is diagrammatically indicated in the drawing may be of the usual form ordinarily employed in toys of the present kind. As indicated in Fig. 2, the spring 8 of the clock-work may be wound-up at the axle 7, which is formed at its outer end as a stud 7' of 50 square cross-section, by means of a key in the well-known manner. The spring 8 during being un-wound rotates the gear-wheels 10, 17 and 11, the intermediate axle 12 and the gear-wheels 13 and 14 as well as the driving axle 5 on which the fly-wheel 6 is eccentrically 55 mounted. The latter may be made on any desired form in accordance with the form of the bird or other animal which shall be represented by the toy. The clock-work is mounted as usual within a frame 4 of sheet-metal, as indicated in Fig. 2, and said frame

4 is placed within the body 1 of the bird and fastened thereto in any desired manner, such as for instance by means of taps or similar fastening means or by means of solder. The clock-work may also be immediately built 70 into the wall of the body of the toy in any desired manner which may be preferable for a desired figure to be represented by the toy. The clock-work may be positioned either symmetrically or asymmetrically with respect to the body of the toy. The axle 5 on which the fly-wheel 6 is mounted may likewise be positioned outside of the plane of symmetry of the body of the toy or of the frame 4 or the clock-work itself. Also the axle 5 may be 75 positioned in any desired direction in order to impart a desired motion to the toy.

The legs of the bird are made from a piece of preferably slightly resilient wire 13' which is bent into the form of a clip and fastened 80 on the body on the bird, for instance, by means of flaps 15 and 15' bent out of the sheet-metal forming the body of the toy. The flaps 85 15 and 15' or other fastening means for the legs may preferably be provided below the 90 tail and the rear part of the body of the bird as indicated in Fig. 3 of the drawing.

I claim:

1. A toy comprising a body representing a bird or other animal, a fly-wheel mounted eccentrically within said body, and means for rotating said fly-wheel, to impart to said toy a reciprocating motion imitating a natural motion of said bird or other animal.

2. A toy comprising a body representing a bird or other animal, a fly-wheel mounted eccentrically within said body, and means for rotating said fly-wheel, to impart to said toy a reciprocating motion imitating a natural motion of said bird or other animal, said fly-wheel in addition to its eccentricity being positioned at some distance from the plane of symmetry of the body to impart thereon an additional one-sided reciprocating motion imitating another natural motion of said bird or other animal.

3. A toy comprising a body in the form of a bird, a fly-wheel mounted eccentrically within the front part of said body, and driving means for said fly-wheel to impart an alternating motion to said body, to imitate the natural picking motion of a bird.

4. A toy as specified by claim 3, having legs made of a bent piece of wire, and means for fastening said piece of wire to said body to properly project therefrom, said fastening means consisting of a pair of flaps provided on the tail-part and another pair of flaps provided on the rear body-part of the bird, said flaps being bent around said piece of wire.

5. A toy comprising a body of a bird, a fly-wheel eccentrically fixed upon an axle, means for rotatably mounting said axle within said body, driving means for rotating said axle and therewith said fly-wheel eccentrically.

cally thereto, whereby a reciprocating motion may be imparted to said body similar to the picking motion of a bird, and resilient leg-members mounted upon said body, said fly-wheel in addition to its eccentricity being positioned out of the plane of symmetry of said body, whereby an additional one-sided reciprocating motion may be imparted thereto, said one-sided reciprocating motion in connection with the resiliency of said leg-members imitating the natural hopping or dancing motion of a bird.

In testimony whereof I affix my signature.

HEINRICH MÜLLER.
